CLOTH LAYING MACHINE

Maximilian Breth, Ozone Park, N. Y.

Application January 11, 1939, Serial No. 250,375

20 Claims. (Cl. 270—31)

This invention relates to cloth laying machines.

It is particularly directed to a device for laying cloth in layers on a table, and comprises a carriage mounted on rollers, and adapted to be rolled back and forth on the table to lay cloth from a roll or bolt of cloth rotatably supported on said carriage, onto the table.

Heretofore, the table on which the carriage reciprocates has been provided with a longitudinal rail, engaging guide means on the carriage, so that the carriage will not roll off the table as it reciprocates; and the carriage has been made adjustable in width to accommodate cloths of different widths. Cloth laying apparatus in which the rail means is eliminated has also been known, but in such apparatus the carriage was of fixed width, being provided with means to engage the opposite side edges of the table to prevent the carriage from rolling off while reciprocating. Such carriages cannot be adjusted for laying cloths of different width. It is therefore an object of the present invention to provide apparatus of the character described, having means to adjust the distance between the side frame of the carriage to accommodate various widths of cloth, and also having means to prevent the carriage from rolling off the table, without the need for a rail on the table, or guide means on the carriage to engage such a rail.

A further object of this invention is to provide in cloth laying apparatus of the character described, including a carriage carrying a bolt or roll of cloth, and reciprocable on a cloth laying table, means on the carriage adapted to be pushed to the right or left for moving the carriage to the right or left, respectively; means controlled by the first means to prevent the carriage from rolling off the cloth laying table, and means to prevent the roll or bolt of cloth thereon from unwinding unless said last means is moved one way or the other, so that if said first means is in its normal central position and the carriage is stationary, the cloth cannot unwind, means being further provided to prevent the carriage from moving on the table unless said first means is pushed one way or the other to ensure against the carriage accidentally rolling off the table.

In cloth laying machines in which a carriage reciprocates on a table to unwind cloth from a roll or bolt of cloth on the carriage onto the table as the carriage is reciprocated, difficulty has been experienced in the cloth laying operation because of air trapped beneath the inclined portion of the cloth extending from the roll or bolt down to the flat, laid portion of the cloth, the air often pre-

venting the cloth from being laid flat and smooth. It is therefore a further object of this invention to obviate this difficulty by providing means to curve said portion of the cloth, whereby to more readily expel the air beneath said portion, so that the cloth may be laid smoothly.

It has been found that as the cloth is laid on the table, upon reciprocating the carriage, the layers of cloth do not always register exactly one with the other. It is therefore a still further object of this invention to provide adjustable spaced guide means adapted to be placed on the table at spaced distances, in the path of movement of the carriage, to insure the cloth being laid in substantially perfectly registering layers.

Still another object of this invention is to provide a strong, rugged and durable machine of the character described, which shall be relatively inexpensive to manufacture, easy to assemble and manipulate, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a side elevational view of a cloth laying machine embodying the invention;

Fig. 2 is an end elevational view thereof;

Fig. 3 is a cross-sectional view taken on line 3—3 of Fig. 1;

Fig. 4 is a cross-sectional view taken on line 4—4 of Fig. 1;

Fig. 5 is a cross-sectional view taken on line 5—5 of Fig. 1;

Fig. 6 is a cross-sectional view taken on line 6—6 of Fig. 5;

Fig. 7 is a cross-sectional view taken on line 7—7 of Fig. 3;

Fig. 8 is a cross-sectional view taken on line 8—8 of Fig. 1;

Fig. 9 is a side view of one end of the shaft for supporting the roll of cloth, with parts in cross-section;

Fig. 10 is a perspective view of a guide member for the layers of cloth, embodying a modified construction; and

Fig. 11 is a view similar to Fig. 9, showing the shaft with an extension thereon.

Referring now in detail to the drawings, 10 designates a table on which cloth is to be laid, and 11 designates a cloth laying machine mounted on the table for reciprocation to lay cloth 5 from a bolt 12 in layers 13 on said table.

The machine 11 comprises a pair of parallel, aligned, vertical frames 14 and 15 of substantially A-shape. The frame 15 has downwardly and outwardly inclined legs 16, carrying wheels 10 17 at their lower ends contacting the upper surface of the table 10. At the apex of the legs 16 is an upward extension 17a formed with a semi-cylindrical notch 18, for the purpose hereinafter appearing. Rotatably mounted on said projection 17a is a wheel 19 slightly overlapping notch 18.

The frame 14 has a pair of downwardly and outwardly extending legs 20, and an interconnecting horizontal portion 21. At the apex of the frame 14 is an upwardly extending frame portion 22 formed with a semi-cylindrical notch 23, similar to and aligned with notch 18. Rotatably mounted on said projection 22 is a wheel 24, aligned with wheel 19, and overlapping notch 23 25 to a somewhat greater extent than the overlap of wheel 19 with notch 18.

Within the notches 23 and 18 is a horizontal shaft 80. One end of the shaft 80 rests on the wheel 19. At the forward end of the shaft 80 is 30 a circular groove 81, receiving the wheel 24. This construction prevents shaft 80 from shifting longitudinally. The wheels 19 and 24 are preferably mounted on roller bearings, so as to facilitate rotation of the shaft 80 for unwinding the cloth.

As shown in Figs. 9 and 11, the length of shaft 80 may be increased at one end to accommodate longer rolls or bolts of cloth, when the distance between the frames 14 and 15 is increased. To this end, the outer end of shaft 80 is provided 40 with a screw threaded opening, at 81a. Attached to the outer end of shaft 80 is a tip member 82, having a reduced screw threaded stem 83, screwed within the opening 81a. When it is desired to lengthen the shaft 80, member 82 is unscrewed.

There is then screwed to member 80 an extension rod 80a, having at one end, a reduced screw threaded stem 84, similar to the stem 83, and screwed within the screw threaded opening 81a. The rod 80a is furthermore formed at its other 50 end, with a screw threaded opening 85a similar to the screw threaded opening 81a, and member 82 may be attached to the outer end of rod 80a by screwing the stem 83 thereof into the screw threaded opening 85a.

On the shaft 80 are a pair of longitudinally adjustable hub members 80b, supporting the roll of cloth 12.

Adjustable means is provided to interconnect the frames 14 and 15, permitting the distance between said frames to be varied. To this end, there is fixed to each of the legs 16 of frame 15, vertically aligned studs 85. Receiving each stud is one end of a horizontal transverse tube 86, fixed to said stud in any suitable manner. Fixed in any suitable manner within the forward ends of the tubes 86 are internally screw threaded members 87.

Fixed to each of the legs 20 of frame 14 are a pair of housing members 88, each provided with 70 a wall 89 contacting the inner surface of one of the legs 20, and a wall 89a parallel to wall 89, and provided with a stud 95, aligned with one of the studs 85. The walls 89, 89a and stud 95 of each member 88 are formed with aligned through openings 89b, and journalled in said through

openings is an elongated rod 90, having a screw threaded portion 91 engaging the threads of the internally screw threaded member 87.

Telescoping with each of the tubular members 86 is a tubular member 96, one end whereof receives one of the studs 95, and is fixed thereto in any suitable manner. Fixed to each of the rods 90, and disposed between the walls 89, 89a of each housing 88, is a sprocket wheel 92. The sprocket wheels 92 are interconnected by a sprocket chain 10 93. One of the rods 90 projects forwardly of a frame leg 20, and fixed to the forwardly extending portion of said rod, is a handle 98.

It will now be understood that upon rotating the handle 98, rods 90 will be rotated in the same 15 direction causing longitudinal movement between the telescoping tubes 86 and 96 to regulate the distance between frames 14, and 15, whereby rolls or bolts of cloth of different widths may be accommodated on shaft 80.

Extending downwardly from the lower ends of the legs 20 are vertical aligned portions 25 formed with similar rectangular openings 26, and with screw threaded openings 27 below said rectangular openings. Fixed within each opening 26 is a 25 member 28 having parallel, horizontal walls 29 passing through and contacting the upper and lower edge of said opening. The walls 29 are interconnected by a flat, vertical front wall 30 contacting the front surface of wall 25 of the 30 frame leg. The walls 29 pass rearwardly beyond the frame and are formed with aligned openings 32 and 33. The lower opening 33 is screw threaded, as shown in Fig. 8 of the drawings, for the purpose hereinafter appearing. The front 35 wall 30 of member 28 has an opening between the top and bottom walls 29 so as to provide a horizontal opening or passage 35, through the member 28.

The front wall 30 of each member 28 is formed 40 with an opening 40, registering with opening 27. Extending through the openings 40 and 27 is a screw 41 to fix a member 28 to each wall 25 of the frame legs 20.

Extending through each opening 35 is a horizontal shaft 36 having a vertical through opening 37, registering with the openings 32 and 33. Extending through the registering openings 32, 31 and 33, and screwed to the openings 33 is a vertical pin 38 on which the shaft 36 is swivelled for 60 angular movement about a vertical axis and in a horizontal plane. Mounted on the rear end of each shaft 36 is a wheel 39 similar to the wheels 17, contacting the top of the table 10.

Fixed to the lower end of each frame wall 25, is 55 a member 42. Each member 42 has a vertical wall 43 contacting the rear surface of the lower end of frame wall 25, and is formed with a screw threaded opening 46 receiving the rear end of the screw 41, for attaching said member to said 60 frame wall. Each member 42 has a wall 48 contacting the underedge of the portion 45, and is furthermore formed with a downwardly projecting curved, part-cylindrical wall 50. Each member 42 is furthermore formed with a screw 65 threaded opening 52, concentric with the part-cylindrical wall 50, and screwed to said opening is a downwardly extending pin 54 supporting a ball bearing roller 55 contacting one vertical edge 70 of the table 10.

Interconnecting the forward ends of the shafts 36 is a link 60, having horizontal slots 61 at its outer ends to receive said shafts. The shafts may be connected to the links by vertical swivel pins 62, as shown in Figs. 1 and 8 of the drawing.

It will now be understood that upon moving the link 60 to the right, the shafts 36 will be turned about the pins 38 to move the wheels 39 into planes inclined to the longitudinal edge 57 of the table 10, so that upon pushing the carriage to the right, the rollers 55 will be retained in contact with the edge 57 of the table to prevent the carriage from running off the table.

Upon moving the link to the left, the shafts 36 are swiveled about the vertical pins 38 in an opposite direction, to incline the wheels 39 in the opposite direction relative to the longitudinal edge 57 of the table, so that upon moving the carriage to the left, the rollers 55 will again be caused to press against the edge of the table, and hence prevent the carriage from rolling off the table.

Means is provided for moving the link 60 to the right when the carriage is moved to the right, and for moving said link to the left as the carriage is moved to the left. To this end, there is fixed to the leg connecting portion 21 of the frame 14, a central bracket 70 extending downwardly below the link 60, and pivoted to the lower end of the bracket, as at 71, is an upwardly extending handle 72, the upper end whereof is offset away from the frame 14, so that the handle may be grasped without contacting the frame. The handle 72 is interconnected to the link 60 above the pivotal connection 71 by a vertical pivot pin 73.

The bracket 70 has a slot 70a through which the handle 72 projects, and is provided with stop edges 70b and 70c at the ends of the slot, located on opposite sides of the pivot pin 71, serving to limit oscillation of the handle 72 in opposite directions.

It will now be understood that when the handle 72 is moved to the right, the link 60 will be moved to the right. When said handle is moved to the left, the link 60 will be moved to the left. When the operator desires to move the carriage to the right, he merely grasps the handle and pushes to the right, until stop edge 70c is contacted, causing the link 60 to be moved to the right for tilting the wheels 39. Continued pressure on the handle will cause the carriage to move, but because of the tilt of the wheels, the carriage will not roll off the table. At the end of the movement of the carriage in one direction, the operator merely presses the handle to the left until stop edge 70b is contacted, and continues pushing, for moving the link 60 to the left, for tilting the wheels 39 in an opposite direction, and moving the carriage to the left.

Means is provided to prevent the roll 12 from unwinding, except when the carriage is being moved by the handle either to the right or to the left. To this end there is fixed to the frame 14, a bracket 100 formed with a vertical opening 101. The interconnecting portion 21 of the frame is furthermore formed with a vertical opening 102 aligned with the opening 101.

Slidably mounted within the openings 101 and 102 is a vertical rod 103. Fixed to the rod 103 is a member 104 interconnected to the frame portion 21 by a coil tension spring 105. The spring 105 normally serves to pull the rod 103 downwardly. At the upper end of rod 103 is an offset portion 106, supporting a brake shoe 107, adapted to press against the underside of the wheel 24 when the rod 103 is raised.

Means is provided to raise the rod 103 for applying the brake to the wheel 24, when the handle 72 is in central or vertical position, that is,

when the carriage is pushed neither to the right nor to the left. To this end, there is fixed to rod 103 a lug 108, formed with a socket 109 on its underside. The handle 72 is formed with a rearward projection 110, provided with a spring 5 pressed pin 111 adapted to be received within the socket 109 when the handle is in central position. The underside of member 108 is curved upwardly and the upper surface of the extension 110 is oppositely curved, so that when the handle is moved 10 towards central position, it will engage the underside of member 108 to raise rod 103 for applying the brake 107 to the wheel 24. The pin 111 serves to retain the handle in central position unless the handle is pushed to the right or to the 15 left. Thus, unless the handle is moved one way or the other, the brake is applied to the wheel, so that the bolt will not accidentally unwind.

Means is further provided to prevent the carriage from being moved unless the handle is 20 pushed to the right or the left, whereby the carriage cannot be moved without tilting wheels 39 in the proper direction to prevent the carriage from rolling off the table. To this end, the pivot pin 71 is provided with a rearwardly extending 25 lug 112, to which is pivoted a bell crank lever 113. The upper end of the bell crank lever is pivotally connected, as at 114, to the lower end of rod 103. On the bell crank lever is a socket 115 supporting a brake 116 of soft rubber or any 30 other suitable material, adapted to contact the upper surface of the table 10, when the handle 72 is centrally located, and the rod 103 is raised. When the handle is in its central position, the carriage cannot be moved because of the engagement of the brake 116 with the table. However, when the handle is moved to the right or the left, the brake is instantly released by spring 105 to 35 permit movement of the carriage.

It has been found that as cloth is laid from a 40 reciprocating carriage, the inclined portion 12a of the cloth extending from the roll 12, down to the laid layers 13, usually traps air which prevents the cloth from being laid smoothly. Means is therefore provided to obviate this difficulty. To 45 this end, there is fixed to each tubular member 96, a radially extending member 120, inclined downwardly and toward the other tubular member. Each member 120 is formed with a groove 121 at its outer end.

Fixed to the inner end of each tube 96, as at 50 122, is a member 123 made of sheet material, curved longitudinally and fitting within the groove 121. Said member 123 may also be curved transversely. Fixed to the inner end of each tube 55 86 is a member 125, overlapping and contacting the member 123, and likewise received within said groove 121. Member 125 may be provided with inturned lugs 126, slidably engaging the opposite edges of member 123.

It will be noted that the members 123 and 125 form an inwardly curved support, adapted to be contacted by the cloth 12a, so as to belly the portion 12a of the cloth at the middle, whereby to facilitate expelling of the air as the cloth is 60 laid, so that the cloth may be laid smoothly.

It will now be understood that as the carriage is moved to the right, the portion 12a of the cloth will contact the curved support on one side, and as the carriage moves in an opposite direction, said portion of the cloth will contact the curved support on the opposite side. As the distance between the frames 14 and 15 is adjusted, the members 123 and 125 will move slidably, one with respect to the other.

Means is provided to insure substantially perfect registry of the layers 13 of cloth laid on the table 10. To this end, there is placed on the table 10 at suitable intervals of about a foot or two, a cloth guide 130. Each guide comprises a pair of similar, symmetrically disposed angle shaped members 131. Each member 131 comprises a horizontal inwardly extending portion 132 and a vertical upwardly extending portion 133. Said portions 132 and 133 are transversely curved, as shown in the drawings. Attached to the underside of the horizontal portion 132 of one member 131 is a flattened tube 134, and attached to the underside of the horizontal portion of the other member 131, is a member 135 telescoping within said tube. With this construction the distance between the members 131 may be adjusted depending upon the width of the cloth. By aligning the guides 130 and adjusting said guides to the proper length, the layers 13 will be laid in substantially perfect registry.

It will be noted that the upper ends of portions 133 are curved upwardly and outwardly, so as to facilitate laying of the cloth.

As shown in Fig. 10, the guide means may comprise pairs of similar, symmetrical, unconnected members 140, placed in alignment on the table, at suitable distances, to guide the laid layers of cloth. The members 140 are of angle shape, comprising walls 141 and 142 disposed at right angles to each other. The wall 142 may be longer than the wall 141. Said walls 141, 142 are curved transversely, and the outer ends thereof are likewise curved, so that the outer edges of the walls 141, 142 are in planes at right angles to one another.

At the beginning of the cloth laying operation, the longer wall 142 is in horizontal position, but when the layers pile up, the member 140 may be withdrawn and turned around so that the shorter walls 141 are in horizontal position beneath the pile, and the longer walls 142 extend upwardly. By transversely curving the walls 141, 142, greater strength is obtained, and the layers are better guided during the cloth laying operation.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. Cloth laying apparatus comprising a carriage adapted to reciprocate on an elongated table, comprising a pair of vertical parallel frames, means interconnecting said frames, means on one of said frames to engage one longitudinal edge of the table, a shaft on said frame swingable about a vertical axis, and a wheel on said shaft contacting the top of the table.

2. In a cloth laying machine, a carriage, a pair of shafts pivoted to said carriage about vertical axes, wheels rotatably mounted on said shafts and adapted to contact the top of said table, and a link interconnecting said shafts, for swinging said shafts in the same direction simultaneously.

3. A cloth laying machine comprising a pair of parallel vertical frames, means to intercon-

nect said frames, wheels on one of the frames adapted to contact the top of a table, a roller on the other of said frames adapted to contact a longitudinal edge of said table, a shaft pivoted to said last mentioned frame about a vertical axis, and a wheel rotatably mounted on the shaft and contacting the top of the table adjacent said edge, said shaft being swingable about its vertical axis to opposite sides of a plane through said axis and perpendicular to said edge of said table. 10

4. In combination with a table having longitudinal edges, a carriage mounted thereon for reciprocation, and comprising a pair of parallel adjustably connected frames, means on one of said frames to contact one longitudinal edge only of said table, said other frame being independent of and movable relative to the other edge of the table as the distance between said frames is adjusted, and means operable by movement of the carriage longitudinally of the table and without pressure on the carriage transversely to the table, to cause the means contacting the edge of the table to press against said edge as said carriage is reciprocated on said table to prevent the carriage from running off the table. 25

5. In a cloth laying machine, a carriage adapted to be reciprocated on a cloth laying table, means on the carriage to support a roll of cloth adapted to be unwound as the carriage is reciprocated on the table, to lay the cloth on the table in layers, a member mounted on said carriage for pivotal movement about a vertical axis, a wheel rotatably mounted on said member and disposed in a vertical plane and adapted to contact the top of said table, means on said carriage to engage a longitudinal edge of the table, said member being swingable about its vertical axis to opposite sides of a plane passing through said vertical axis, and perpendicular to said longitudinal edge, as said carriage is reciprocated on said table. 30

6. In combination with a cloth laying machine, a carriage adapted to be reciprocated on a cloth laying table, means on the carriage to support a roll of cloth adapted to be unwound as the carriage is reciprocated on the table, to lay the cloth on the table in layers, a member mounted on said carriage for pivotal movement about a vertical axis, a wheel rotatably mounted on said member and disposed in a vertical plane 50 and adapted to contact the top of said table, means on said carriage to engage one longitudinal edge only of the table, said carriage being independent of the other longitudinal edge of the table, said member being swingable about its vertical axis to opposite sides of a plane passing through said vertical axis, and perpendicular to said longitudinal edge, as said carriage is reciprocated on said table. 55

7. In a machine of the character described, a carriage comprising a pair of parallel vertical interconnected frames, a pair of parallel, similar members pivoted about vertical axes on one of said frames, a link pivoted to said members, wheels disposed in vertical planes, rotatably mounted on said members, and a pair of rollers rotatably mounted on said frame about vertical axes adapted to contact one vertical edge of said table. 60

8. In a machine of the character described, a carriage comprising a pair of parallel vertical frames, means interconnecting said frames, a pair of parallel, similar members pivoted about vertical axes on one of said frames, a link pivoted to said members, wheels disposed in vertical 70 axes adapted to contact one vertical edge of said table.

cal planes, rotatably mounted on said members, a pair of rollers rotatably mounted on said frame about vertical axes adapted to contact one vertical edge of said table, a shaft for supporting a 5 roll of cloth, wheels rotatably mounted on said frames, said shaft being supported on said wheels, and means to apply a brake to one of said wheels.

9. In a cloth laying machine, a carriage adapted to be reciprocated on a table, a rotatable 10 shaft on said carriage, adapted to support a roll of cloth to be laid on said table, means on said carriage adapted to engage a longitudinal edge of said table, means on said carriage to press said last means against said edge of said table as 15 the carriage is reciprocated, whereby to prevent the carriage from rolling off the table, and means controlled by said pressing means to retain said shaft against rotation.

10. In a cloth laying machine of the character described, a carriage adapted to be reciprocated on a cutting table comprising a pair of parallel vertical frames, means interconnecting said frames, a pair of parallel, similar members pivoted about vertical axes on one of said frames, 20 a link pivoted to said members, wheels disposed in vertical planes, rotatably mounted on said members, a pair of rollers rotatably mounted on said frame about vertical axes adapted to contact one vertical edge of said table, a shaft for 25 supporting a roll of cloth, wheels rotatably mounted on said frames, said shaft being supported on said wheels, means to apply a brake to one of said last mentioned wheels, and means to retain the carriage against movement on the 30 table.

11. In a cloth laying machine, a carriage adapted to be reciprocated on a table, a rotatable shaft on said carriage, adapted to support a roll of cloth to be laid on said table, means on said carriage adapted to engage a longitudinal edge of said table, means on said carriage to press said last means against said edge of said table as the carriage is reciprocated, whereby to prevent the carriage from rolling off the table, 40 means controlled by said pressing means to retain said shaft against rotation, and means controlled by said pressing means to retain the carriage against movement on the table.

12. In a cloth laying machine, a carriage 50 adapted to be reciprocated on a table, means on the carriage to support a bolt or roll of cloth to be laid on the table in layers as said carriage is reciprocated thereon, and bowed means to engage a portion of the cloth between the roll or bolt and the topmost layer laid on the table, to press the longitudinal mid-portion thereof toward the table to facilitate laying of the cloth smoothly on the table.

13. In a cloth laying machine, a carriage 60 adapted to be reciprocated on a table, means on said carriage to support a bolt or roll of cloth to be laid on the table, said carriage comprising a pair of parallel vertical frames, a transverse member interconnecting said frames, and a longitudinally curved member supported by the first member, and adapted to contact the central portion of the cloth as it is unwound from the bolt or roll of cloth on the carriage.

14. In a cloth laying machine, a carriage 70 adapted to be reciprocated on a table, means on the carriage to support a roll or bolt of cloth adapted to be laid on the table as the carriage is reciprocated thereon, and means on the table to guide the layers of cloth laid on the table,

said means having a horizontal wall, and a vertical wall extending upwardly from the horizontal wall.

15. A carriage adapted to be moved back and forth on a trackless table, means on said carriage adapted to contact one edge only of said table and being independent of the other edge of the table, and rotary means on the carriage, adapted to contact a horizontal surface of the table, means to shift said rotary means about a 10 vertical axis to press said first means in engagement with said edge of said table.

16. A carriage adapted to be freely rolled back and forth on a trackless table, means on said carriage adapted to contact an edge of said 15 table, and means on the carriage adapted to contact a horizontal surface of the table, for keeping said first means in engagement with said edge of said table, said last means comprising a shaft hinged to said carriage about a vertical axis, 20 and a wheel rotatably mounted on said shaft and contacting said horizontal surface of said table.

17. A carriage adapted to be freely rolled back and forth on a trackless table, means on said 25 carriage adapted to contact an edge of said table, means on the carriage adapted to contact a horizontal surface of the table, for keeping said first means in engagement with said edge of said table, said last means comprising a shaft 30 hinged to said carriage about a vertical axis, a wheel rotatably mounted on said shaft and contacting said horizontal surface of said table, and means on said carriage to swing said shaft about its vertical axis.

18. A carriage adapted to be rolled back and forth on a trackless table, means on said carriage to support a bolt of cloth to be laid on the table, means to prevent the carriage from rolling off the table, comprising a member rotatably 40 mounted on the carriage on an axis other than at right angles to the edge of the table, and adapted to engage a horizontal surface of the table, and means on the carriage engaging one edge of the table.

19. In a cloth laying machine of the character described, a carriage adapted to be reciprocated on a cutting table, comprising a pair of parallel, vertical frames, means to interconnect said frames, a pair of parallel shafts pivoted 50 about vertical axes on one of said frames, a link interconnecting said shafts, wheels rotatably mounted on said shafts, rollers rotatably mounted on said frame about vertical axes, a shaft for supporting a roll of cloth, wheels rotatably 55 mounted on said frames, said shaft being supported on said wheels, a brake for one of the last mentioned wheels, and means controlled by said link to apply the brake to one of said last mentioned wheels.

20. A carriage adapted to be moved back and forth on a trackless table, means on said carriage adapted to contact one edge only of said table, said carriage being independent of the other edge of the table, and means on the carriage, operable by movement of the carriage longitudinally of the table in opposite directions and without external pressure on the carriage transversely of the table, to cause the edge contacting means to press against said edge to prevent 65 the carriage from running off the table as the carriage is reciprocated on said table.
